UNITED STATES PATENT OFFICE

JOHN B. GORMLEY, OF ROXBURY, MASSACHUSETTS

MONOGRAM STRUCTURE

Application filed December 30, 1931. Serial No. 583,859.

My present invention relates to monogram structures and more particularly to a monogram structure preferably made of metal which may be cemented to leather goods such as traveling bags, suitcases and the like.

In my present invention I have designed a monogram structure having a letter receptacle in which monogram letters formed on metal inserts may be assembled easily and quickly without the aid of adhesive of any kind. Heretofore monogram structures have been constructed such that monogram letters might be inserted in the monogram structure and held thereto by cement or other kinds of adhesive. In such devices there has always been more or less difficulty in mounting such letters by salesmen and the like without some of the adhesive pressing out under the material on which the monogram letter is placed and resulting in an unsightly appearance. Likewise the monogram structure itself is cemented to leather material such as travelling bags. Prior structures of this class have been difficult to attach neatly because the fixing material more or less roughly applied to the back of the structure presses out beyond the outer edge of the structure. In my present device I have provided for such contingencies and have designed letter receptacles in the monogram structure adapted to receive any combination of monogram letters desired therein and hold the letters without the use of any adhesive.

The principal object of my invention is therefore an improved monogram structure.

Another object of my invention is an improved monogram letter receptacle in combination with the monogram structure.

A further object is an improved means for mounting a monogram structure on leather goods and the like.

Other objects and novel features comprising my invention will appear as the description of same progresses.

Referring to the drawing illustrating the preferred embodiment of my invention, Fig. 1 illustrates a front elevation of a monogram structure, the particular design of which plays no important part in this application.

Fig. 2 shows a rear elevation of said structure.

Fig. 3 is a cross-section taken on the line 3—3 of Fig. 1.

Fig. 4 is a fragmentary cross-section similar to Fig. 3 showing the method of mounting the monogram letter units in the structure.

Referring more in detail to the drawing, 10 indicates a base in which are provided 60 openings 11. The openings 11 as shown in Fig. 2 actually represent the outline of flanges 12 better shown in Figs. 2 and 3 and indicated in dotted lines in Fig. 1. On the front side of the structure the opening 11 is composed of the straight sides 13, 14 and 15, one of the narrow sides having a beveled recess 16 and the opposite short side 17 having a recess 18. In addition the short side 17 is beveled as shown in Figs. 3 and 4. A 70 thin metal monogram letter member 19 is provided at one of its short sides with a beveled edge 20 adapted to be inserted in the beveled recess 16. When mounting the monogram letter member 19 the beveled edge 20 is first inserted in the beveled recess 16 after which pressure is applied as shown in Fig. 4 to snap the opposite end into the recess 18. It should be understood that member 19 is of relatively thin metal and the recesses 18 75 and 16 and likewise beveled sides 17 of the structure are greatly exaggerated in Figs. 3 and 4 for illustrative purposes. In a like manner all the letter receptacles are constructed similarly to the central one just described merely being duplicates thereof.

On the back of the structure 10 is an annular recess 21 and also recesses 22. The recesses 22 result from the openings 11 which appear on the back side 23 of the monogram structure as shown in Fig. 2. When the letter inserts are passed through the openings 11, they are received against the flanges 12 thereby forming the recesses 22, comprising the surface 23 which is the back side of the metal insert and the edges of the flanges 12. When the structure is applied to a surface and firmly pressed down, the annular recess 21 acts as a trap to catch surplus cement or other adhesive which tends to press outward 100

to the circumference of the structure thereby eliminating the necessity of cleaning any surplus cement which otherwise might be squeezed out around the circumference of 5 the structure on the leather or other material upon which the structure is mounted. It will be seen that any combination of monogram letters may be easily, quickly and neatly mounted in the structure 10 and the entire 10 structure securely and neatly mounted on the object upon which it is to be used with a minimum requirement of time and skill.

Having thus described my invention what I claim is:

15 1. A monogram structure adapted to adhere to leather goods and the like comprising a base, an annular recess located in the back surface of said base and adjacent its periphery for the purpose of trapping excess adhesive applied to the back of said base for mounting purposes, openings cut through said monogram structure, resilient units comprising monogram letter plates removably locked within said openings, recesses 20 located in the back surface of said base adjacent the back side of said letter plates adapted to trap adhesive applied to the back side of the said monogram structure.

2. A monogram structure adapted to adhere to leather goods and the like comprising a base, an annular recess located in the back surface of said base and adjacent its periphery for the purpose of trapping excess adhesive applied to the back of said 30 base for mounting purposes, removable units comprising monogram letter plates adapted to be secured within said base, a recess located between the back surface of said base and said letter plates adapted to receive and hold said adhesive, the sides of said recess comprising a flange adapted to receive said letter plate, two opposite sides of said flanged recess provided with internal recesses adapted to receive two opposite ends 35 of said letter for the purpose of securing said letter plate in said base.

3. A monogram structure comprising a base, openings cut therethrough, resilient units comprising monogram letter plates, 40 and internally recessed flange portions located on the inner edges of said openings, said letter plates being removably locked within said recessed flange portions.

4. A monogram structure comprising a 45 base, an annular recess located in the back surface of said base and adjacent its periphery for the purpose of trapping excess adhesive applied to the back of said base for mounting same, a plurality of openings cut 50 through said monogram structure provided with internally recessed flange portions located on the inner edge thereof, resilient units comprising monogram letter plates removably locked in said flanged portions, said 55 flanged portions and said letter plates form-

ing recessed areas on the back side of the said monogram structure adapted to partly receive and trap excess adhesive applied to the said back side.

In testimony whereof I have affixed my 70 signature.

JOHN B. GORMLEY.
